UNITED STATES PATENT OFFICE

WILLIAM KIRCHNER AND FRANK J. SHELDON, OF SPARTA, WISCONSIN

TURNING AND HEADING MACHINE

Application filed July 29, 1927. Serial No. 209,304.

This invention relates to improvements in turning and heading machines, and although the invention is primarily adapted for use in the manufacture of posts, it is also readily adaptable for various other uses.

The invention has for its object to provide a machine wherein a post or other object may be turned down to the desired size and shape or otherwise wrought upon and which, coincident with the turning operation, heads or shapes the extremity of the post without requiring any additional work on the part of the operator.

A further object of the invention is the provision of a machine wherein the cutter and header elements are both driven from a common driving source.

A further object of the invention is the provision of a carriage for the work and means for yieldably advancing the carriage as the cutting operation progresses and for returning the carriage to initial position after the completion of a post.

A further object is the provision of means for permitting interruption in the operation of the work piece during return movement of the carriage.

A further object of the invention consists in the embodiment in a machine of the character described of such structural features as tend to increase its efficiency and convenience of operation without, however, involving structural complication or unnecessary expense of manufacture.

In the accompanying drawing:

Fig. 1 is a top plan view of the machine;

Fig. 2 is a side elevation thereof;

Fig. 3 is a view similar to Fig. 1 showing the carriage advanced to a position to engage the work with the heading cutter;

Fig. 4 is a section on the line 4—4 of Fig. 3;

Fig. 5 is a transverse section through the frame and carriage;

Figs. 6 and 7 are detail views of the main and head cutters, respectively;

Fig. 8 is a partly sectional end view from the right hand end of the parts as shown in Figure 1, representing the arrangement of the friction drive wheels;

Fig. 9 shows a side view of the yoke shaped

auxiliary holder fixed to the side rail as set forth in Figure 3.

Referring to the drawing in detail:

The numeral 5 indicates a suitable supporting structure on which the side rails 6 are mounted, the latter constituting a combined support and guide for the carriage 7 which is movable longitudinally of the guide rails 6. A work support and actuating means is provided as shown comprising a driving member or chuck 8 mounted on the carriage 7 and provided with work clamping screws or equivalent means 9 by which the work is rigidly clamped in the support or holder 8. The opposite extremity of the work piece is centered by a tail stop 10 which is borne by the extremity of the carriage 7.

A sprocket wheel 11 is fixed to the rotatable work holder 8 and coating with a chain 12 is driven by a sprocket wheel 13 carried by a shaft 14 journalled in bearings 15 carried by one of the rails 6. The shaft 14 is slotted from end to end and the wheel 13 is slidably keyed thereon, being moved along the shaft incident to travel of the carriage by a yoke shaped member 16 fixed to the carriage 7 and having forked extremities embracing the shaft 14 and confining the wheel 13.

The shaft 14 from which rotary motion is imparted to the work holder 8 is driven from a shaft 17 through the medium of gear wheels 18.

A pair of shafts 19 and 20 mounted on the guide rails 6 coat with a flexible cable 21 to effect feeding and return movements of the carriage 7. The extremities of the cable are wound about the respective shafts 19 and 20 and extending longitudinally of the frame, constituted in part by the rails 6, are engaged at the opposite end of the latter over a guide pulley 20^a supported by the transverse shaft 20^b borne by the ends of the side rails as set forth in Figure 1, the cable being fixed intermediate its extremities to an arm 21^a carried by a cross member 21^b of the carriage 7, whereby rotation of one or the other of the shafts 19 or 20 effects longitudinal movement of the carriage 7 in the desired direction.

One extremity of each shaft 19 and 20 is journalled on a common bearing 22 which is

slidably mounted on the adjacent rail 6, and is moved from one position to the other by a lever 23 pivotally secured to a rail 6 and connected with the bearing 22. The opposite extremities of the shafts 19 and 20 are suitably mounted to permit the necessary lateral movement of the first mentioned ends incident to sliding movement of the bearings 22. The bearings 22 for the transverse shaft 19, and the like bearings for the fellow transverse shaft 20 are carried by base plate 22^a which rests and slides lengthwise upon the side rails 6, and as the lever 23 is operated the friction wheels 25 are alternately brought into engagement with the driven friction wheel 24. Each shaft 19 and 20 carries a friction drive wheel 25 and these are alternately engageable with a central drive wheel 24 fixed to the shaft 17.

25 A belt or other power transmitting element 27 is trained over a wheel 28 fixed to the shaft 17 and is engaged at opposite ends over a pulley fixed to the drive shaft 29 on which the main cutter 30 is fixed. The cutter 30 is preferably journalled in a bearing 31 and is interchangeable so as to permit variation of the shape and diameter of the work turned out.

30 At the extremity of the frame opposite the shaft 29 the heading cutter 32 is provided mounted on a shaft 33 journalled in bearings 34 and driven from the shaft 29 by a belt 35. The purpose of this heading cutter is to head or shape the end of the work, that is, to give the end of the post the shape desired. In the drawings the specific heading cutter employed is designed to give the end of the post a rounded appearance, although it will be readily understood that it may be given various other configurations as desired depending on the character of heading cutter employed. The size and shape of the cutter 32 may be adequately varied according to the desired shape of the post or other work to be turned out, and as the latter approaches the cutter 32 it is partially embraced and supported by a yoke shaped auxiliary holder 36 fixed to one of the side rails 6.

35 In order that the rotary movement of the shaft 14 and consequently the holder 8 and work may be temporarily interrupted during the return movement of the carriage 7, a clutch 37 is interposed between the shaft 17 and gear wheel 18, and may be conveniently operated in any suitable manner.

The operation of the machine is extremely simple requiring merely the setting and clamping of the work in the holder 8 together with proper adjustment of the main cutter 30 and the selection of a heading cutter 32 of the desired shape. Upon shifting the lever 23 to engage the proper friction wheel 25 with the drive wheel 24 the carriage is advanced by the cable 21 and the cutter 30 turns the work down to the desired size. As

the terminal of the work approaches the cutter 32 it is embraced by the holder 36 and held in position where, coincident with the operation of the cutter 30, the post is headed by the cutter 32.

70 A further important feature of the invention consists in that the tail stock 10 is capable of adjustment by means of a slot and screw connection 10^a permitting it to be displaced laterally with respect to the axis of 75 the machine whereby posts of tapering form may be turned.

The work holder 8 is further provided with a downwardly projecting pillar 9^a secured to the cross member 21^b by screw 9^b. To move so the axial line of the work sidewise in order that a tapering post may be turned an adjustment of the tail stock 10 and work holder 8 are correspondingly made.

What we claim is:

1. A turning machine including a frame, a carriage movable therein, work supporting and rotating means mounted on said carriage, a main cutter mounted on said frame, and a cutter for shaping the end of the work, the cutters being so positioned and the work supporting and rotating means being so arranged that at least a portion of one end of the work shall be exposed and so that the work shall be rotated and carried by the carriage past the main cutter to shape the length of the work while the exposed portion of the end of the work is brought up against the end shaping cutter to be shaped thereby at the end of the travel of the work.

2. A turning machine including a frame, a carriage movable therein, work supporting and rotating means mounted on said carriage, a main cutter mounted on said frame, and a cutter for shaping the end of the work, the cutters being so positioned and the work supporting and rotating means being so arranged that at least a portion of one end of the work shall be exposed and so that the work shall be rotated and carried by the carriage past 105 the main cutter to shape the length of the work while the exposed portion of the end of the work is brought up against the end shaping cutter to be shaped thereby at the end of the travel of the work, and an auxiliary work holder engageable by and for supporting the work as the latter approaches the end shaping cutter.

In testimony whereof we affix our signatures.

WILLIAM KIRCHNER.
FRANK J. SHELDON.
